UNITED STATES PATENT OFFICE

152,957

DESIGN FOR A BEDSPRING FABRIC

Nathan C. Goldberg, New York, N. Y.

Application May 15, 1947, Serial No. 139,059

Term of patent 14 years

(CL. D5—2)

To all whom it may concern:

Be it known that I, Nathan C. Goldberg, a citizen of the United States, residing in the Borough of Manhattan, county and city of New York, State of New York, have invented a new, original, and ornamental Design for Bedspring Fabric, of which the following is a specification, reference being had to the accompanying drawing, forming part thereof.

Fig. 1 is a top plan view of a bedspring fabric showing the new design of this invention.

Fig. 2 is a similar plan view, showing a smaller area of the new design, upon a larger scale, to bring out more clearly certain elements constituting parts of the design.

Fig. 3 is a vertical section of the elements shown in Fig. 2, taken on the section line 3—3 of Fig. 1.

The dominant features of my design reside in those portions of the drawing which are shown in full lines.

I claim:

The ornamental design for a bedspring fabric, substantially as shown and described.

NATHAN C. GOLDBERG.
